POWER-OPERATED VENTILATOR

Fred H. Gohl, Chicago, Ill., assignor to Chicago Blower Corporation, Chicago, Ill., a corporation of Illinois

Application November 10, 1950, Serial No. 195,094

3 Claims. (Cl. 98—43)

1. This invention relates to a power operated ventilator, and more particularly to a centrifugal fan having an axially disposed inlet and an annular discharge outlet which particularly adapts the ventilator for use in a roof installation or the like.

It is an object of this invention to provide a ventilator of the character described which has a relatively low noise level and yet which provides an efficient flow of air under all conditions of use, which flow is greatly superior to that produced by a centrifugal fan of ordinary design.

Another object is to provide a ventilator of the character described which incorporates cut-off type air guiding vanes which shear off the air at the peripheral edge of the fan wheel, which shearing action permits the fan to operate against static pressures unknown in ordinary centrifugal roof ventilator design.

Yet another object is to provide a ventilator of the character described in which the air is sheared off the edge of the wheel at approximately every 60° of angular rotation, and in which the air is discharged in a complete 360° arc, through an annular discharge passage which is so disposed and designed as to keep discharge losses at a minimum.

Still another object is to provide a ventilator of the character described in which the cut-off vanes at the peripheral edge of the centrifugal fan or wheel are so disposed in opposing angular relation to the vanes of the fan wheel that the noise level and efficiency of the fan when operating are at a desirable minimum and maximum, respectively.

A further object is to provide a power operated ventilator of the character described in which a positive flow of air is maintained through that portion of the ventilator housing the source of power.

Further objects and advantages of this invention will become evident as the description proceeds and from an examination of the accompanying drawing which illustrates one embodiment of the invention, and in which similar numerals refer to similar parts throughout the several views.

In the drawings:

Figure 1 is a view in side elevation and partly in vertical cross-section of one form of ventilator embodying this invention; and

Figure 2 is a view in horizontal cross-section with parts broken away, the view being taken along the line 2—2 of Figure 1.

Referring now to Figure 1, a ventilator, indi-

cated generally by the numeral 10, is disclosed therein mounted in association with a curb 12, which may be formed as an integral part of a roof, for example. The ventilator is provided with a base member 14 adapted to fit over the curb 12 and having a central opening 16 therein which is in communication with the opening 18 in the curb 12. The base 14 may have an inlet collar 20 mounted thereon in dual alignment therewith in the form of a shallow truncated cone having its edge of lesser diameter uppermost.

A collar member 22 of larger diameter than inlet collar 20 is provided which also may have the form of a truncated cone and have its edge of greater diameter secured to the base member 14, the collar member 22 being disposed in axial alignment with and encompassing relation to the inlet collar 20. A plurality of upstanding angularly disposed air baffle plates 24 may be provided which may be secured at the base thereof to the inlet collar 22, so that they extend upwardly therefrom into fixed and supporting relation with the base 26 of the substantially cylindrical housing 28. As best shown in Figure 2, these air baffle plates 24 are symmetrically disposed about the inlet collar 22, and have an angular relation such that each forms substantially the same angle with a line drawn tangent to the circular opening in the inlet collar 22 at the point at which the inner edge of each such baffle plate substantially coincides with that circular opening.

Immediately below the central opening 30 in the base 26 of the cylindrical housing 28, a fan wheel 32 is disposed in axial alignment with the center of the opening 16 in the base member 14 and the circular opening in the upper end of the inlet collar 20.

The fan wheel 32 may be composed of the inclined blades 34, as best shown in Figure 2, the circular plate 36 to which the upper edge of the blades 34 are adapted, as by welding, the substantially conical plate 38 to which the lower edges of the blades 34 are similarly attached, and the hub 40. As shown in Figure 1, the conical plate 38 may have a lip 35 formed on its edge of lesser diameter which is disposed in overlapping relation with a similar lip formed on the upper edge of the inlet collar 20. The edge of greater diameter of the conical plate 38 is in relatively close association with the edge of lesser diameter of the collar member 22. The ultimate result is that the fan wheel 32 is mounted so as to have an axially aligned inlet associated with the circular opening in the inlet collar 20.

and so that its peripheral edge is disposed in relatively close association with the inner edges of the angularly disposed air baffle plates 24.

The fan wheel 32 is secured to the shaft 42 by the hub 40, the shaft 42 being journalled in suitable bearings (not shown), carried by the bearing and motor housing 46, which is in turn supported by vibration dampeners, such as 48 and 50. The upper end of the shaft 42 has the pulley wheel 44 secured thereto. The electric motor 52 is mounted in the motor and bearing housing 46, and has the pulley wheel 54 secured to the shaft thereof and disposed in substantially the same plane as the pulley wheel 44, so that the latter may be driven thereby through the use of a V-belt or the like. The housing 28 may be suitably enclosed by the removable cover 56.

A skirt or collar member 58 in the form of a truncated cone may be provided at the lower edge of the housing 28, the collar member 58 being disposed so as to extend downwardly and outwardly in substantial parallel relation to the collar member 22. This disposition of the collar members 58 and 22 provides an annular discharge passage 60, which has the angularly disposed baffle plates 24 disposed at the inner periphery thereof.

When the ventilator is in operation, the fan wheel 32 is rotated in a counter-clockwise direction, as indicated by the arrow 59 in Figure 2. Since the inclined blades 34 are disposed in angularly opposed relation to the baffle plates 24, a definite shearing action occurs as the air is thrown outwardly from the periphery of the fan wheel 32 when it rotates rapidly. As previously mentioned, this shearing action of the baffle plates 24 permits the fan wheel 32 to operate against static pressures previously unknown in roof ventilator design. The discharge losses are kept to a minimum by permitting the air which is sheared off the edge of the fan wheel 32 to be discharged through the discharge passage 60 in a complete 360° arc.

In addition to the improved efficiency provided by the power operated ventilator which is the subject matter of this invention, with respect to the movement of the air out through the discharge passage 60, a very desirable and novel ventilation of the motor compartment is provided. This ventilation is produced by having the upper edge of the fan wheel disposed immediately below the horizontal plane of the base 26 of the housing 28, and in axial alignment with the opening 30 therein. The centrifugal action of the fan wheel 32, in addition to forcing the air out through the discharge passage 60, will therefore cause a reduction of air pressure within the housing 28, and will insure a positive air movement through the housing 28, which air will enter between the cover 56 and the upper edge of the housing 28, and will pass through the motor compartment and then down into the discharge passage 60 through the opening 30 in the base 26 in the housing 28. Such a circulation of air through the motor compartment is, of course, very desirable.

The drawing and the above discussion are not intended to represent the only possible form of this invention, in regard to details of construction. Changes in form and in the proportion of parts, as well as the substitution of equivalents, are contemplated, as circumstances may suggest or render expedient, without departing from the spirit or scope of this invention, as further defined in the following claims.

What is claimed is:

1. A power operated ventilator comprising a fan housing having an axially disposed inlet and an annular discharge outlet, a multi-bladed power driven fan rotatably disposed in said housing, with its axis of rotation substantially coincident with the axis of said inlet, the annular discharge outlet being disposed in substantial alignment with the outer edge of the blades of said fan, a collar member forming a part of said housing substantially in the form of a truncated cone having the edge of lesser diameter disposed in close association with the lower edge of said blades, a plurality of upstanding air baffle plates disposed on said collar member in close association with said blades but in angularly opposed relation thereto, a substantially cylindrical portion of said housing having the upper ends of said air baffle plates secured thereto being disposed immediately above and in axial alignment with said fan, the base of said cylindrical portion having a centrally disposed opening therein in substantial alignment with said fan, a second collar member in the form of a truncated cone having its edge of lesser diameter secured to the lower edge of said cylindrical portion of said housing, said collar members being disposed in substantially parallel relation so as to form an annular passage in communication with said annular discharge outlet.
2. A power operated ventilator comprising a substantially cylindrical housing, a prime mover disposed in said housing, a shaft axially aligned with and depending from said housing adapted to be rotated by said prime mover, a multi-bladed fan mounted on the depending portion of said shaft, the base of said cylindrical housing having an opening therein in substantial alignment with said fan, a plurality of angularly disposed air baffle plates depending from the base of said cylindrical housing having their inner edges in close association with the blades of said fan, a collar member substantially in the shape of a truncated cone having its edge of lesser diameter disposed in close association with the lower edge of said blades, and having the lower extremities of said air baffle plates secured thereto, a base member to which the opposite edge of said collar member is secured, an inlet cone disposed within said collar member having its lower edge secured to said base member and its upper edge extending into close association with said fan, and a second collar member substantially in the shape of a truncated cone having its edge of lesser diameter disposed in secured relation to said cylindrical housing and protruding outwardly in substantially parallel relation to said first named collar member, said collar members and said base of said housing therefor forming a substantially annular discharge passage communicating with the peripheral edge of said multi-bladed fan.
3. A power operated ventilator comprising an annular base member having a central opening therein, a collar member substantially in the form of a truncated cone having the edge of greater diameter secured to said annular base member, a plurality of upstanding, angularly disposed air baffle plates disposed on said collar member and extending upwardly into association with the base of a substantially cylindrical housing, said base of said housing having a centrally disposed opening therein, a multi-bladed

below said opening in said base of said housing, the outer edges of the blades of said fan being disposed in close association with the inner edges of said air baffle plates and the edge of lesser diameter of said collar member, an ⁵ inlet cone secured to said base member and axially aligned with the opening in said base member and said fan member, the edge of lesser diameter of said inlet cone being disposed in close association with the base of said fan, a second ¹⁰ collar member substantially in the form of a truncated cone having the edge of lesser diameter secured to the lower edge of said housing and protruding outwardly in substantially parallel relation to said first named collar member, said collar members and said base of said

housing therefor forming a substantially annular discharge passage communicating with said fan.
